Primary Examiner — Derrick Holland(74) *Attorney, Agent, or Firm* — Fay Sharpe LLP(57) **CLAIM**

The ornamental design for an I/O module, as shown and described.

DESCRIPTION

FIG. 1 is a front isometric view of an I/O module showing the new design;

FIG. 2 is a rear isometric view of the I/O module showing the new design;

FIG. 3 is a left side view of the I/O module showing the new design;

FIG. 4 is a top view of the I/O module showing the new design;

FIG. 5 is a bottom view of the I/O module showing the new design;

FIG. 6 is a front view of the I/O module showing the new design;

FIG. 7 is a right side view of the I/O module showing the new design; and,

FIG. 8 is a rear view of the I/O module showing the new design.

The broken lines in the drawings are used to depict environment and form no part of the claim design. Where broken lines abut a claimed surface it is understood that those broken lines represent an unclaimed boundary between claimed and unclaimed surfaces. None of the broken lines form any part of the claimed design.

1 Claim, 4 Drawing Sheets(56)
